UNITED STATES PATENT OFFICE.

WILLIAM D. PARKER, OF WORCESTER, MASSACHUSETTS, ASSIGNOR TO THE MUNROE ORGAN REED COMPANY, OF SAME PLACE.

PNEUMATIC ACTION FOR MUSICAL INSTRUMENTS.

SPECIFICATION forming part of Letters Patent No. 368,165, dated August 9, 1887.

Application filed February 21, 1887. Serial No. 228,305. (No model.)

To all whom it may concern:

Be it known that I, WILLIAM D. PARKER, a citizen of the United States, residing at Worcester, in the county of Worcester and State of Massachusetts, have invented certain new and useful Improvements in Pneumatic Actions for Musical Instruments, of which the following, together with the accompanying drawings, is a specification sufficiently full, clear, and exact to enable persons skilled in the art to which this invention appertains to make and use the same.

The objects of this my present invention are to provide a simple and efficient pneumatic valve-action adapted to be used in connection with a set of reeds, and which will occupy but small space in the instrument, and which can be manufactured with economy and facility, while affording a durable and superior action, and one which will operate with promptness and ready response to the controlling means. These objects I attain by mechanism the construction, nature, and operation of which are explained in the following description, the particular subject-matter claimed being hereinafter definitely specified.

In the drawings, Figure 1 is a transverse vertical section of my improved pneumatic action. Figs. 2, 2^a, and 2^b are horizontal sections at lines v v, w w, and x x, respectively. Fig. 3 is a horizontal section at line y y, looking downward. Fig. 4 is a horizontal section at the same position, looking upward. Fig. 5 is a section through one of the valve-chambers, separate from other parts. Fig. 6 is a separate perspective view of one of the valve-puppets. Fig. 7 is a longitudinal vertical section at line z z, Fig. 1.

In reference to parts, A denotes the wind-chest from which air is to be exhausted. This may be done with any suitable form of organ-bellows or wind-inducing mechanism of ordinary construction, connected at the passage a for operation in the usual manner.

B indicates the tube-block resting upon the reed-board C, and provided with cells b, in which reeds R or sound-producing devices are arranged in the usual manner as employed in reed-organs, orguinettes, and similar instruments. The reed-block B and tube-board C

are made of any length desired to fit the instrument, or to accommodate a set of any desired number of reeds. The reeds are disposed therein at the usual spacing or distance apart, as employed in the scale of regular-sized organ-reeds, or as indicated in Figs. 2 and 7, and the usual oblong slot or air-passage, e, is formed, substantially as in the ordinary manner, through the reed-board beneath each of the respective reeds. The relative position of said slots is indicated in Figs. 2 and 2^a by dotted lines at e.

The top or board A' of the wind-chest is made with a series of circular openings, d, arranged in alternating order in two rows, the openings in each row corresponding with and opening alternately into the respective passages C in the manner illustrated. Said openings d serve as chambers in which the valves D work. The valve is made as a puppet, or with a circular disk having a centrally-disposed depending stem or spindle, D', which supports and guides the valve in its action, as will be hereinafter explained.

On the under side of the board A', or within the wind-chest A, is the valve-seat plate E, consisting of a board having a series of circular holes or passages, e, corresponding in position with the chambers d, or so that the respective openings e and d will match when placed together and form a continuous wind-way, through which the air passes on its way from the sounding device or reeds R into the wind-chest A. The openings e are counter-bored from the lower side, or formed in such manner as to leave a ledge or inwardly-projecting annular flange, f, about the opening, which flange or ledge serves as a seat for the valve D, which rests thereon. The top surface of the valve-seat plate E is preferably covered with a cushion or packing, E', of soft leather or other suitable material, so as to prevent any rattling of the valves or leakage of air between the plate E and top board, A'.

Guide-bars F are arranged across the openings e, through which the spindle or stem D' of the valves is extended, suitable holes being formed in said guide-bars axially coinciding with the openings e and chambers d for the reception of said valve-spindle. These holes

are of such size as will confine the spindles D' sufficiently to prevent the valve from swaying laterally off from its seat, while at the same time permitting the free upward and 5 downward movement of the valve. The guide-bars F are preferably let into longitudinal grooves formed in the plate E, as shown at g, Figs. 1 and 5.

The valve D is opened by lifting it upward 10 from the seat f in opposition to the pressure of air induced by the exhaustion of the chamber A. The counterbore or enlargement of the opening e below the valve-seat allows ample space for click action of the current the 15 instant the valve leaves its seat, thus affording quick and full response of the sounding devices.

Below the valve-seat plate is arranged a 20 pneumatic bed, H, having on its upper side a series of pneumatic motors, I, respectively corresponding in position with the positions of the valves D, and constructed substantially as shown in Figs. 1 and 3, which is as follows:

Shallow recesses are formed in the upper 25 surface of the bed H, from which windways or passages h extend to the edge of the bed-board H, as indicated in Fig. 1. A sheet of thin leather, H', or other suitable fabric is secured to the top surface of the board, covering 30 the several recesses and forming thereover the flexible diaphragms on which the disks of the pneumatics are secured in a manner that will permit them to rise and fall as the relative air-pressure within and above the recesses is varied. The sheet of leather H' may 35 form the diaphragms of the entire series of pneumatics I in a single piece, if desired.

A strip of paper or fabric, K, is arranged over the ends of the openings h, and a pin-hole is perforated through said strip of paper 40 into each of the windways or passages h.

The pneumatic bed H is arranged at a convenient distance below the valve-seat plate E, so as to leave a chamber or air-space between 45 the two, which air-space opens into the wind-chest, as clearly shown in Fig. 1.

A windway-block, L, having a series of air-passages, l, through it, is arranged between the bed-piece H and top board, A'. The passages l connect the passages h with windways w, leading from the tracker-range T, over which a perforated music-sheet, M, may be passed to act as a valve for opening and closing the series of windways, and thereby controlling the 55 inlet of air to the respective pneumatic diaphragms and governing the action of the devices in accordance with the music to be performed.

If preferred, manual keys or any other suitable well-known means may be employed for regulating the inlet of air at the windways w and controlling the action in lieu of a perforated music-sheet.

In the construction herein shown it will be 65 noticed that the valves D are entirely free and disconnected from other parts, save that they are confined in axial alignment by the guide,

so that they can fall by gravity when the pneumatic motor or lifting device is relieved from pressing on the stem D'. 70

It will also be noticed that the closing of the valve is in a direction coincident with the direction in which the air-current passes through the windway; hence the air-pressure occasioned by the wind-inducing apparatus, acting upon 75 the area of the valve, assists in closing the valve, and also serves to hold it down to its seat when closed. The stronger the pressure the more tightly will the valve hold.

The area of the pneumatic diaphragm requires to be but slightly greater than that of the valve, since both work under the same degree of pressure, and the diaphragm has only to overcome the "pluck" of the valve and to lift the weight of the valve and disk, which is 80 comparatively slight, there being no springs or other counter forces to overcome. Thus the action is rendered very light and capable of instant movement under slight variations of the air-pressure, giving quick response and facility 85 for playing allegro passages of music.

The guide-bar F serves as a stop for the pneumatic disks when exploded or inflated, as well as for guiding the valve-stems. The disks are preferably capped with a soft-packing-cushion, as i, to avoid rattling against said bar, or the cushion material may be attached 90 to the guide-bar.

By alternating the valves D and the pneumatic devices in two rows, as illustrated, the mechanism is brought within the regular scale or spacing of standard-sized organ-reeds, and sufficient room is also afforded for the circular pneumatics, valves, and valve-chambers. 100

The improvement may be employed in reed-organs, automatic organs, and other musical instruments of a similar nature. 105

The operation of my improved action is as follows: Air being let into one of the ducts or passages w when the air in the chamber A is 110 exhausted, the pneumatic I, corresponding therewith, is inflated, thereby throwing its disk upward toward or against the guide-bar F. This movement lifts the valve D from its seat, so that air will be drawn down through the 115 windway, chamber, or space surrounding said valve, and the sounding of the corresponding reed thereby effected. Then, when the wind-duct w is again closed from the external air, equalization of pressure above and below 120 the pneumatic diaphragm is established by the leakage of air from the passage h through the pin-hole K, and the atmospheric pressure, acting on the disk of the valve, forces down said valve and the pneumatic diaphragm, and also 125 causes the valve to cling to its seat by reason of excess of pressure on its upper surface.

Among the advantages incident to my invention may be mentioned its simplicity of construction and great convenience in arrangement and grouping of parts; also, its great promptness and efficiency of action and its strength and durability for service. 130

The valves are brought directly beneath the

reeds, as well as into the scale or spaces corresponding with the reeds. The action of the valves is quick, free, and positive, no springs of any kind whatever being required or used 5 in connection with the parts. There is no liability of any of the parts becoming deranged or jarred out of place in shipping and handling the instrument.

The parts can readily be duplicated, thus 10 rendering the cost of construction comparatively small, while affording great facility in manufacture.

What I claim as of my invention, and desire to secure by Letters Patent, is—

15 1. In a musical instrument, the combination, with a reed and reed-cell having a windway leading into a wind-chest, of a puppet-valve disposed within said windway to close in the direction of the air-current, and provided with a guiding and supporting stem, whereby the valve is retained in proper relation to its seat while free to work to and from the same, and a pneumatic device unattached 20 to but engaging the lower end of said stem 25 for forcing said valve from its seat in opposition to the air-pressure upon the valve-surface, substantially as set forth.

2. In a musical instrument, the combination, with the reed or sounding device, of a 30 puppet or valve for opening and closing the air-duct thereof, disposed between said reed and the wind-chest, to be closed to its seat by the pressure of air occasioned by the wind-inducing apparatus acting upon the valve-area, a pneumatic actuating-motor disposed 35 within the wind chest and acting by inflation to open said valve, the air-inlet passage leading from the interior of said pneumatic motor to the exterior of the wind-chest, and means 40 for opening and closing said air-passage, substantially as and for the purpose set forth.

3. A musical instrument having a set of 45 sounding devices or reeds, R, with their windways formed of the passages e, alternating series of chambers d, into which said passages open, and series of correspondingly-disposed openings e, the valve-seat ledges f, the valve-puppets D, arranged within said chambers and

provided with dependent stems D', a series of 50 pneumatic motors, I, respectively disposed within the wind-chest beneath said valves and provided with windways leading to a tracker-range, and means for controlling the inlet of air to said motors, substantially as set forth.

4. The combination of a set of reeds with 55 air-passages e, arranged in ordinary scale or spacing, a series of valve-chambers disposed alternating in two rows beneath said reed-set and communicating, respectively, with said air-passages, valves D, arranged within said chambers, and a series of pneumatic lifting diaphragms and disks disposed in corresponding 60 alternating order beneath said valves, substantially as and for the purpose set forth.

5. In a musical instrument, the combination 65 of a reed-duct valve, D, having a stem or lifting-pin, a pneumatic motor operating in conjunction with said valve-stem for raising said valve, and a guide-bar, as F, which serves as a guiding-support for the valve-stem and as 70 a stop for the inflative action of the pneumatic motor, substantially as set forth.

6. In a musical instrument, the combination 75 of a reed-board, C, having reeds and windways e, opening into valve-chambers d, the valve-seat plate E, having openings e, the guide-bars F, the valves D, having stems D', that pass through said guide-bars, the bed H, having the circular pneumatics I, axially coincident 80 with said valve-stems, air-passages leading from the tracker-range to the interiors of said pneumatics, with vents at K, and means for controlling the air-pressure within said pneumatics, substantially as set forth.

7. The valve-seat plate having openings 85 which are counterbored to form the seating-edges f, in combination with the valve-puppets, guide-bars F, chambers d, and valve-operating devices, substantially as set forth.

Witness my hand this 15th day of February, 90 A. D. 1887.

WILLIAM D. PARKER.
